CAN PUNCH

Edwin Albert Briner, Seattle, Wash.

Application April 7, 1950, Serial No. 154,538

2 Claims. (Cl. 30—6.1)

1

This invention relates to new and useful improvements and structural refinements in can punches, and the principal object of the invention is to facilitate convenient, safe and expeditious puncturing of cans preparatory to pouring out their contents.

An important feature of the invention resides in the provision of a can punch which may be quickly and easily adjusted so as to accommodate cans of different diameters as well as of different types.

Some of the advantages of the invention reside in its simplicity of construction, in its convenient operation as aforesaid, and in its adaptability to economical manufacture.

With the above more important objects and features in view and such other objects and features as may become apparent as this specification proceeds, the invention consists essentially in the arrangement and construction of parts as illustrated in the accompanying drawings, in which:

Figure 1 is a side elevational view of the invention;

Figure 2 is a top plan view thereof;

Figure 3 is a fragmentary sectional view, taken substantially in the plane of the line 3—3 in Figure 1;

Figure 4 is a sectional view, taken substantially in the plane of the line 4—4 in Figure 2;

Figure 5 is a fragmentary sectional view, taken substantially in the plane of the line 5—5 in Figure 2;

Figure 6 is a fragmentary sectional view, similar to that shown in Figure 5 but on an enlarged scale;

Figure 7 is a perspective view of a carrier used in the invention; and

Figure 8 is a sectional view, taken substantially in the plane of the line 8—8 in Figure 1.

Like characters of reference are employed to designate like parts in the specification and throughout the several views.

Referring now to the accompanying drawings in detail, the invention consists of a can punch which is designated generally by the reference character 10 and embodies in its construction an upright standard 12, preferably in the form of a channel having a U-shaped cross-section, the lower end of this standard being provided with a horizontally elongated base 14 which may also be in the form of a U-shaped channel having its side flanges extending upwardly, while its web portion rests on a suitable supporting surface, as is best shown in Figure 8.

2

A box-shaped carrier 16 is slidable vertically on the standard 12 and is provided with a pair of transversely spaced, apertured ears 18 to receive a horizontal pivot pin 20 on which is mounted one end portion of a lever 22 for swinging movement in a vertical plane.

The lever 22 may also assume the form of a U-shaped channel and the inner, pivotally mounted end portion thereof is provided with a longitudinally projecting tongue 24 which is receivable selectively in a vertical row of apertures 26 provided in the standard 12. In other words, when the lever 22 is swung downwardly to a substantially horizontal position, the tongue 24 extends into one of the apertures 26 and, by thus preventing the carrier 16 from sliding on the standard 12, the lever 22 is sustained in a predetermined position or at a predetermined height above the base 14. However, by simply swinging the lever 22 upwardly to the position shown in Figure 5 by the dotted lines 28, the tongue 24 is disengaged from the apertures 26 so as to facilitate sliding of the carrier 16 on the standard 12 and, at the same time, permit the height of the lever 22 above the base 14 to be adjusted.

A channel-shaped sleeve 30 is slidable longitudinally on the lever 22 and is provided with a tubular handle 32, the inner end portion of the sleeve 30 being provided with a downwardly projecting can-piercing element 34 while a similar element 36 projects downwardly from the pivoted inner end portion of the lever 22.

The base 14 is adapted to support a can 38 which is to be punched, and if desired, an upwardly projecting detent 40 may be provided on the outer end portion of the base for properly locating the can, while the inner end portion of the upstanding flanges of the base may be formed with transversely aligned notches 42 for locating cans which have a downwardly projecting bead or rim at the lower end thereof.

In any event, when the invention is placed in use, a can 38 is positioned on the base 14 against the standard 12 and the carrier 16 is slid on the standard so that it is disposed somewhat above the upper end of the can, as shown in Figure 1.

The lever 22 is then swung downwardly by means of the handle 32 so that when it reaches a substantially horizontal position, the tongue 24 will enter one of the apertures 26 to lock the carrier 16 against sliding on the standard, while at the same time the piercing elements 34, 36 will puncture the upper end of the can at diametrically opposite points. It is to be noted that by simply

sliding the handle 32 together with the associated sleeve 30 on the lever 22 the spacing of the piercing element 34 from the piercing element 36 may be increased or decreased so as to accommodate cans of different diameters, while the adjustment facilitated by the slidability of the carrier 16 on the standard 12 will enable the invention to accommodate cans of different heights.

It is believed that the advantages and use of the invention will be clearly understood from the foregoing disclosure, and further description thereof at this point is deemed unnecessary.

Having described the invention, what is claimed as new is:

1. In a can punch, the combination of a base 15 plate, an upright standard secured to said base plate, said standard comprising a channel-shaped member having a back portion provided with a vertical row of apertures and a pair of forwardly projecting flanges, a carrier slidable on said standard and including a front wall having a pair of transversely spaced lugs, a pair of side walls slidably engaging said flanges, and a pair of spaced inturned back wall portions provided at the rear edges of said side walls and slidably engaging said back member at the opposite sides

of said row of apertures, a lever pivoted at one end thereof to said lugs for swinging in a vertical plane, a can piercing element projecting downwardly from said lever, and a tongue constituting a longitudinal continuation of the pivoted end of said lever, said tongue being receivable selectively in said apertures when the lever is swung downwardly but being retractable therefrom when the lever is raised.

5 10 2. The device as defined in claim 1 together with a handle slidable on said lever, and a second can piercing element carried by and projecting downwardly from said handle.

EDWIN ALBERT BRINER.
